The ornamental design for an electrocoagulation reactor, as shown and described.

DESCRIPTION

FIG. 1 is a side view of an electrocoagulation reactor showing our new design;

FIG. 2 is a perspective view thereof;

FIG. 3 is a front view of a cover thereof;

FIG. 4 is a perspective view thereof, with the cover removed;

FIG. 5 is a front view of the electrocoagulation reactor as shown in FIG. 4, wherein the electrodes have been removed from the electrode stack; and,

FIG. 6 is a perspective view of the electrode stack comprising electrode plates.
